ABRAHAM M. ERICHSEN, OF BERLIN-STEGLITZ, GERMANY

CHILL MOLD FOR CASTING NONIRON METALS

Application filed October 24, 1928, Serial No. 314,762, and in Germany November 2, 1927.

Chill-molds for casting iron containing metals are known, the walls of which consist of a nickel-iron-alloy with up to 20% contents of nickel, in order to obtain a soft metal 5 casting and to extend the durability of the chill-mold.

The present invention relates to chill-molds for casting non-iron metals and their alloys, such as brass, German silver, etc., also precious metals in plates, ingots, or bolts, worked by rolling, pressing, drawing into sheets, bars, wires, etc. According to the present 10 invention, these chill-molds are made entirely or partly of a metal or metal-alloy of inferior heat-conducting-capacity, which latter amounts to only about one third of the heat-conducting-capacity of cast-iron, or one sixth of the heating-conducting-capacity of soft-iron. An iron-nickel-alloy containing over 15 20% nickel, preferably about 35%, is particularly adapted thereto, being by special treatment rendered badly heat-conducting, but other badly heat-conducting metals and metal-alloys are likewise coming into consideration.

As proved by experiments, non-iron metals cast in such molds, solidify considerably slower and more uniform than in ordinary chill-molds.

20 While the cast-iron surface sinks in the latter during transition into the solidified state and considerable waste is being produced thereby, the chill-molds, made in accordance with the present invention of badly 25 heat-conducting metals show the peculiar quality that the casting-compound is not piping during the transition into the solid state as hitherto, but has the tendency to rest at the surface of the casting, or expand more or 30 less over the casting-surface. Casting-waste is hereby reduced to an utmost minimum. Castings of brass, or the like, produced by means of the novel chill-molds show furthermore a lighter colour, having to be traced 35 back to another crystalline composition, it being considerably finer in the castings made by means of the novel chill-molds and showing also a finer formation of grains, while the late, quicker solidification of the castings, 40 produced a coarser crystalline structure.

Metal-squirts on the chill-mold-wall do not cool off, or at least very slow, and can therefore not form any flaws in the casting.

Consequent to the slower solidification, the gases and oxides have time to escape in an upward direction. 55

The structure of the casting is therefore favourably influenced by the novel chill-mold for further working into sheets, or the like, pipes or other defects are not formed inside 60 the casting, or flaws on the surface of the same.

The novel chill-mold can, instead of entirely, only partly consist of badly heat-conducting metal, as it may be of advantage to produce in a thick, or wide metal-plate of brass a more uniform solidification of the metal thereby, that the plate is in the middle coming into contact with a better heat-conducting metal than at the sides, in order that the 65 plate may not have the tendency to solidify on the sides quicker than in the middle, whereby the formation of pipings might be produced in the middle of the plate. It may likewise be advantageous to provide the upper part of the mold with a badly heat-conducting material in order to keep the runner for a longer time liquid. 70

The novel chill-mold can also be designed as cooling-mold for continuous working, whereby the cooling-liquid is supposed to keep the chill-mold possibly permanently at the casting-temperature, or bring the temperature of the chill-mold after casting again back to the initial temperature. This cooling has however in the new chill-mold hardly any influence upon the solidification, as the radiation of heat is correspondingly retarded by the badly heat-conducting metal between the liquid metal and the cooling-water. 80 Cooling, or re-cooling of the new chill-mold by means of the cooling-medium will naturally be effected more slowly. 85

The chill-mold-wall may in its entirety consist of badly-heat-conducting metal, for some purposes, an insulating layer of badly heat-conducting metal will however be sufficient, being placed by squirting-process upon another material, or welded upon another plate. 95

It is, of course, to be understood that plates of badly heat-conducting metal can be screwed, or fastened in any other suitable manner to the walls of ordinary known cast iron chill molds.

- 5 Two modes of embodying the invention have been illustrated by way of example in the drawing by a cross-section through the chill-mold.
- 10 In Fig. 1, *a* represents the chill-mold of cast-iron, or other suitable metals, made in two parts, being on the whole inner surface provided with a layer, or plate *b* of badly heat-conducting metal, so that the metal casting *c* is all around coming into contact with the badly heat-conducting metal. The layer, or plate *b* can, as stated, be squirted, welded, screwed or otherwise fastened upon the mold *a*.
- 15 In Fig. 2, the arrangement has thus been made, that the inner surface of the chill-mold, in two parts, coming into contact with the metal casting *c*, consist of metal or a metal-alloy of different heat-conducting capacity. At both sides of the mold, a layer, or plate *b* of badly heat-conducting metal is provided, while in the center at *d* better heat-conducting metal is provided. The center parts *d* can be formed by the chill-mold
- 20 *a* of cast-iron or other suitable metals. This construction is particularly adapted for plate-casting, as the cast plate *c* will thereby solidify in the center approximately within the same time as at the sides.
- 25 The entire chill-mold may of course be made of badly heat-conducting metal or a metal-alloy.
- 30 The design and production of the other parts of the chill-mold may differ, the parts of the mold may be connected flexibly folding, or otherwise.

I claim:

1. A chill mold for casting non-iron metals consisting of a metal of bad heat conducting capacity amounting to substantially one-third of the heat conducting capacity of cast iron.
- 45 2. A chill mold for casting non-iron metals consisting of a metal alloy of bad heat conducting capacity amounting to substantially one-third of the heat conducting capacity of cast iron.
- 50 3. A chill mold for casting non-iron metals consisting of a metal of bad heat conducting capacity of below 0.05 caloric unit per 0.4 inch thickness per second and degree (C.).
- 55 4. In a chill mold for casting non-iron metals, a layer of a metal of bad heat conducting capacity amounting to substantially one-third of the heat conducting capacity of cast iron, connected to the chill mold and forming the inner walling of the mold.
- 60 5. In a chill mold for casting non-iron metals, a layer of a metal of bad heat conduct-

ing capacity amounting to substantially one-third of the heat conducting capacity of cast iron, connected to the chill mold and forming the inner walling of the mold, and a layer of a better heat conducting metal at the center of the mold and at the surfaces of the latter contacting with the liquid metal, whereby to obtain a uniform solidification over the entire casting.

In testimony whereof I affix my signature.

ABRAHAM M. ERICHSEN.
